Application January 7, 1953, Serial No. 329,980

5 Claims. (Cl. 251—16)

This invention relates to so-called fuses for altering or interrupting fluid flow after a predetermined volume of fluid has passed through the fuse.

The fuse of the present invention is sensitive only to flow and will remain open until the flow aggregates a predetermined volume regardless of the number of interruptions which occur during the passing of such volume. The fuse will be opened and reset only by return or reverse flow, but will reset on a very small volume of return flow compared to that necessary to close the fuse. The fuse valve, having low inertia, accelerates readily, and the fuse may therefore be made sensitive to a wide range of flow rates; and its bulk density is the same as that of the fluid, thereby rendering it insensitive to external inertia and gravity forces. A simplified holding device prevents resetting of the fuse except on return flow.

The nature of the invention and further details thereof will be readily apparent from the following description of one illustrative fuse embodying the invention as shown in the accompanying drawing.

In said drawing:

Fig. 1 is a longitudinal section through the fuse;

Fig. 2 is a fragmentary longitudinal section on an enlarged scale of the improved holding device; and

Fig. 3 is a fragmentary section on an enlarged scale showing the mounting of the orifice to permit by-passing on return flow.

The illustrative fuse is an improvement over that shown in Stark Patent 2,592,487, reference to which is made for a detailed statement of the purpose and function of fuses of this character.

The illustrative fuse is provided with inlet and outlet fittings 10 and 11 for connecting it (by conventional threaded couplings in this case) in a fluid line. The major portion of the flow travels through the fuse unrestricted, entering at inlet 10 and directed by the conical head 12 through the annular passage 13 leading to valve port 14, the latter surrounded by valve seat 15. A very small fraction of the fluid (exactly proportional to that traveling unrestricted through passage 13) passes through metering orifice 16 (reaching it through one or more lateral or radial holes 17 in head 12) and displaces the valve piston 18 toward its seat at a rate proportional to the flow rate of fluid through the fuse. The metering orifice is advantageously formed in a removable orifice plate 19, loosely resting between bushing 21 and spacer 22 in head 12. Enough clearance is provided between the spacer and bushing to allow the orifice plate to be lifted on return of piston 18 to permit the fluid freely to by-pass metering orifice 16 (traveling around the edge of plate 19), thereby to insure a rapid return or resetting of the piston with only a small fraction (e. g. 2%) of the total return flow. A spring retaining ring holds the bushing, spacer and orifice plate in assembled position.

The valve piston and connected parts are advantageously designed to have the same weight as the volume of fluid they displace, thereby making the valve in effect

2

substantially weightless. This eliminates the tendency for the valve to be displaced by external forces such as gravity and inertia (depending upon the position of the fuse) and independently of flow. Heretofore, a light spring has been employed to exert a restraining force sufficient to prevent movement by such external forces, but such spring renders the fuse insensitive to low rates of flow having a pressure drop in the fuse insufficient to overcome the force of the spring. The spring being no longer necessary, the valve is responsive to very low flow forces and it is therefore possible to make it sensitive to any desired minimum flow rate.

In the present instance, the piston is given its low bulk density by making it hollow so that even though it be of metal (e. g. aluminum), its total weight (including attachments such as the holding element in this case) is substantially equal to that of the volume of fluid displaced. Preferably, the cylindrical bearing face of the valve piston extends substantially throughout its length to eliminate binding against the cylinder wall.

The aforesaid holding device, which is in the form of a rod 26, is adapted to hold or lock the piston valve in any advanced position on interruption of flow, and to prevent its displacement by any force except the forces of either forward or return flow. The connection of rod 26 with the piston is preferably loose in a lateral direction, to make absolute concentricity of rod and piston unnecessary. A more detailed explanation of the purpose and function of a holding element of this character will be found in said Stark patent. A flow controlled gripper 27 holds the rod and piston 18 against movement. The gripper is of simplified form, comprising a pair of opposed spring fingers 28 mounted on the rod guide assembly 29. The pressure of each finger on the rod is balanced by that of the other, therefore eliminating any binding action on the valve piston which would increase the forces necessary to move the piston. Unbalanced lateral forces on the valve are very important where, as in the present instance, the valve is subject to high fluid pressures. Valves of this type are subject to working pressures of 3000 pounds per square inch and test pressures 50% higher. Even slight unbalanced pressures are therefore magnified and may result in binding of the valve against the cylinder walls. The fingers normally grip rod 26 and are released by a cam 31 operated by a flow sensitive member in the form of a piston 32. Cam 31 is designed with opposed cam surfaces 33 to release the rod 26 upon longitudinal movement of cam 31 in either direction. Since the valve piston has substantially the same weight as the fluid displaced, the gripper 27 need exert only a light gripping force on rod 26 to hold the piston against response to the aforesaid external forces. The gripper may therefore be actuated to release the rod by light forces, and it and its operating mechanism may be light and compact. This makes it possible to keep friction forces low and render the fuse sensitive (if that be desired) to the minute forces developed at low flow rates.

Piston 32 lies in the path of both forward and return flow, indeed it normally closes the passage between inlet and outlet and opens it only upon resumption of flow in either direction. As here shown, flow from annular passage 13 passes through openings 34 in the sleeve 35 (which acts as the cylinder for piston 18) to reach valve port 14. Openings 34 are restricted only enough to produce a pressure drop sufficient to actuate or displace valve 18 at minimum rates of flow. After passing the port 14, flow enters the annular space 37 around sleeve 35 through openings 36, and travels around the gripper assembly to ports 38 (controlled by piston 32) through which it reaches the outlet fitting 11. A seal in the form

of an O-ring 39 closes the end of annular space 13 obliging all flow to pass through valve 14 where it is cut off upon seating of valve 18 on seat 15.

Piston 32 is normally centered to close ports 38 by a relatively light spring 41. Spring seats 42 and 43 compress the spring upon movement of piston 32 in either direction. Both are slideable towards each other on the cam rod 31 and are located inside spring case 44 comprising a part of the valve gripping assembly.

Fluid pressure from forward flow reaches the companion piston 45 (functionally integral with piston 32), through openings 46, and displaces piston 32 (compressing spring 41) to uncover ports 38 to permit flow to reach outlet 11 through openings 47 in the piston. Such movement of the piston simultaneously operates cam 31 to release gripper 27 to permit forward movement of the valve piston 18 in response to flow. Upon interruption of flow, spring 41 returns piston 32 to close ports 38 and to re-apply gripper 27. Return flow, reaching companion piston 45 through openings 47, also compresses spring 41 by means of spring seat 42, moving piston 32 in the opposite direction to uncover ports 38 and to release gripper 27. On interruption of return flow, spring 41 returns piston 32 to port closing position and re-applies gripper 27. Thus valve piston 18 is held against displacement in both directions by all forces except that of fluid flow through the fuse. It will close on seat 15 if and when the aggregate of successive forward flows (without intervening return flow) equals the predetermined volume for which the fuse is calibrated. The area of piston 32 being large and spring 41 being light, only a very small flow force is required to release the gripper. Pistons 32 and 45 are, however, light in weight, and spring 41 is sufficient to prevent movement of piston 32 in response to inertia and gravity forces. It should be noted, nevertheless, that even though gripper 27 be momentarily released by excessive inertia forces, piston 18 (being in effect weightless) would not be substantially moved by such external forces.

If it be desired to render the fuse insensitive to a certain minimum flow, a small port 49 (here shown formed in piston 45) of a size sufficient to pass such minimum flow, may be employed to pass such minimum flow through the fuse without operating piston 32. When flow increases beyond such minimum it exerts enough force on piston 45 to operate piston 32 to release valve piston 18. A by-pass port of this character may be employed, for example, to render the fuse insensitive to a small amount of harmless leakage which sometimes cannot be prevented. If the valve is to be sensitive to all flow, the size of port 49 is of course zero.

The holding assembly is secured in place by an exterior rib 51 which lies between the end of sleeve 35 and sleeve 52, the latter serving as a cylinder or guide for piston 32.

The several sleeves 35 and 52 with their assemblies, are secured in the surrounding fuse housing 55 by the shoulder 56 adjacent the outlet end of the fuse and by the inlet fitting 10 at the other end of the housing.

Obviously the invention is not limited to the details of the illustrative fuse, since these may be variously modified. Moreover, it is not indispensable that all the features of the invention be used conjointly, since various features may be used to advantage in different combinations and sub-combinations.

Having described my invention, I claim:

1. A hydraulic fuse sensitive to low rates of flow comprising in combination a fuse housing through which flow passes and having a cylindrical bore and inlet and outlet and a valve seat, a valve piston slideable in said housing bore toward and away from said seat in response to flow through said housing, said valve piston being a hollow sealed cylinder substantially the weight of the hydraulic fluid passing through said bore and displaced by said valve piston whereby the latter may be easily held stationary

against the forces of gravity and inertia, said valve piston having a cylindrical bearing surface longer than its diameter and extending substantially the length of said valve piston to minimize the tendency to bind in said bore under inertia forces, a pair of opposed gripping fingers normally exerting opposed gripping forces on said valve piston to hold the same against movement, and an actuating mechanism responsive only to flow through said fuse for releasing said fingers.

2. A hydraulic fuse sensitive to low rates of fluid flow comprising in combination a fuse housing having inlet and outlet and a valve seat, a valve piston slideable in said housing toward and away from said seat in response to flow through said housing, said valve piston being substantially the weight of the said fluid it displaces and thereby requiring only a slight force to hold it against movement by gravity and inertia forces, a gripper comprising a pair of opposed gripper fingers normally applying opposed and balanced gripping forces to said valve piston to hold the same against movement without exerting unbalanced lateral forces thereon, and gripper actuating mechanism responsive only to flow for actuating said gripper to release said valve piston, said mechanism having means operative on cessation of flow to restore said gripper to operative position.

3. A hydraulic fuse sensitive to low rates of fluid flow comprising in combination a fuse housing having inlet and outlet and a valve seat, a valve piston slideable in said housing toward and away from said seat in response to flow through said housing, said valve piston being substantially the weight of the said fluid it displaces and thereby requiring only light forces to hold the same against movement by gravity and inertia forces, a gripper normally applying opposed and balanced gripping forces to said valve piston to hold the same against movement without exerting any unbalanced lateral force thereon, and gripper actuating mechanism responsive only to flow for actuating said gripper to release said valve piston.

4. In a hydraulic fuse for controlling fluid flow the combination comprising a fuse housing having a fluid passage through the same for said flow and an inlet and outlet, a valve seat and a cylindrical bore adjacent said seat in said housing, a piston valve slideable in said bore toward and away from said seat in response to the direction of fluid flow through said passage, and a flow responsive holding device normally holding said piston valve against movement and actuated by flow in either direction to release said piston valve, said holding device having means normally applying opposed holding forces to said piston valve, said piston valve comprising an elongated hollow sealed cylinder having substantially the same weight as the said fluid it displaces thereby requiring little force to hold the same against movement by inertia forces, said cylinder having a bearing face longer than the diameter of said cylinder and extending substantially the length of said piston valve, and a connecting means for connecting said piston to said holding device substantially within the length of said bearing face to minimize the tendency of inertia forces to bind the piston in said bore.

5. In a hydraulic fuse for controlling fluid flow the combination comprising a fuse housing through which said fluid flows and having inlet and outlet and a valve seat, and a cylindrical bore adjacent said seat, a piston valve slideable in said bore toward and away from said seat in response to the flow through said housing, said piston valve comprising a hollow sealed cylinder having substantially the weight of the said fluid it displaces whereby it requires only a light force to hold it against movement by inertia and gravity forces, a flow responsive holding device for holding said piston valve against movement upon interruption of flow, said holding device having means normally applying opposed holding forces to said piston valve, the cylinder having a bearing surface longer

than the diameter of said cylinder and extending substantially the length of the piston valve to minimize the tendency to bind in said housing under inertia forces, and a lost-motion connection for connecting said holding device with said cylinder and lying substantially within the length of said bearing surface.
